Primary Examiner — Catherine Tuttle(74) *Attorney, Agent, or Firm* — Stass & Halsey LLP(57) **CLAIM**

The ornamental design for a toy top, as shown and described.

DESCRIPTION

FIG. 1 is a top perspective view of the toy top showing my design;

FIG. 2 is a front orthographic elevation view thereof;

FIG. 3 is a rear orthographic elevation view thereof;

FIG. 4 is a left side elevation view thereof;

FIG. 5 is a right side elevation view thereof;

FIG. 6 is a top plan elevation view thereof; and,

FIG. 7 is a bottom plan elevation view thereof.

The broken lines are included for the purpose of illustrating portions of the toy top that form no part of the claimed design.
